UNITED STATES PATENT OFFICE.

CHARLES HABERMANN, OF JERSEY CITY, NEW JERSEY, ASSIGNOR TO OSCAR SCHMIDT,
INC., OF JERSEY CITY, NEW JERSEY, A CORPORATION OF NEW JERSEY.

ZITHER-ACTION.

1,181,760.

Specification of Letters Patent.

Patented May 2, 1916.

Application filed July 19, 1913, Serial No. 779,901. Renewed March 25, 1916. Serial No. 86,797.

To all whom it may concern:

Be it known that I, CHARLES HABERMANN, a citizen of the United States, and a resident of Jersey City, in the county of Hudson and State of New Jersey, have invented a new and Improved Zither-Action, of which the following is a full, clear, and exact description.

The invention relates to citherns and similar stringed musical instruments, and its object is to provide a new and improved action arranged to permit the player to readily sound simultaneously a series of bass or accompaniment strings to produce the desired chords in a very simple and effective manner.

In order to produce the desired result use is made of bearing blocks mounted on the body of the instrument at opposite sides of the said bass or accompaniment strings, striking bars extending across the said accompaniment strings and provided at the under side with cushions, crank arms on the ends of the said striking bars and journaled in the said bearing blocks, and springs attached to the said bearing blocks and connected with the said striking bars to move the latter into striking position after being raised and released, the said springs normally holding the striking bars in dormant position with the cushions standing directly above the strings.

A practical embodiment of the invention is represented in the accompanying drawings forming a part of this specification, in which similar characters of reference indicate corresponding parts in all the views.

Figure 1 is a plan view of the stringed musical instrument; Fig. 2 is an enlarged sectional side elevation of the same on the line 2-2 of Fig. 1; Fig. 3 is an enlarged cross section of the same on the line 3-3 of Fig. 1. Fig. 4 is a similar view of the same on the line 4-4 of Fig. 1; Fig. 5 is a like view of the same on the line 5-5 of Fig. 1; and Fig. 6 is a similar view of the same on the line 6-6 of Fig. 1.

The body A of the stringed musical instrument is a box-like structure similar to the ones used in regular citherns, and on the said body A are mounted in the usual manner a set of melody strings B and a set of bass or accompaniment strings C, the sets being preferably spaced apart, as plainly indicated in Fig. 1. On the top of the body

A are secured bearing blocks D and E arranged on opposite sides of the bass or accompaniment strings C, and ranging in the direction of the length thereof, and across the bass or accompaniment strings C extend a series of striking bars F, F', F² and F³ provided at their ends with crank arms G journaled in the bearing blocks D and E to permit the striking bars F, F', F² and F³ to swing up and down. The striking bars F, F', F² and F³ are provided at the under side with cushions H adapted to engage and sound corresponding bass or accompaniment strings C, the cushions on each bar being so arranged relative to the strings to sound a chord whenever a striking bar is actuated, as hereinafter more fully described. It is understood that the cushions H of the several striking bars F, F', F² and F³ are differently arranged so that each striking bar is adapted to sound a different chord as will be readily understood by reference to Figs. 3, 4, 5 and 6. As shown in Fig. 3, the first bar F has its cushions H so arranged that the notes G, E, C, G, C, E are struck and sounded as a chord. The cushions H' of the striking bar F' as shown in Fig. 4 are arranged to sound the notes G, G, B, D as a chord. The cushions H² of the striking bar F² are arranged to strike the notes C, F, A, C, F as a chord as shown in Fig. 5. The cushions H³ of the striking bar F³ as shown in Fig. 6 are arranged to strike and sound the notes G, F, G, B, D, F as a chord.

Springs I, preferably of the coil type, are attached at one end to screws or pins J secured to the bearing block D, and the other end of the springs are connected with the striking bars F, F', F² and F³. The springs I are normally in a relaxed or closed position and while in this position support the striking bars in normal inactive position, that is, with the cushions extending directly above the strings without touching the same, as will be readily understood by reference to Fig. 2. When it is desired to sound a chord the corresponding striking bar F, F', F² or F³ is swung upward by the player so that the corresponding spring I is placed under tension, and when the player releases the raised striking bar then the spring returns the striking bar and in doing so the cushions H of the striking bar engage and sound the corresponding strings to produce the desired chord.

In order to permit convenient upward movement of the striking bars F, F', F² and F³ their tops are provided with finger pieces K adapted to be pressed by the thumb of the 5 player's left hand.

It is understood that when a striking bar F swings downward by the action of its spring I, the latter causes a rebound after the strings are struck by the cushions, so 10 that the latter immediately leave the strings and thus allow the same to fully sound the chord.

By reference to Fig. 2, it will be noticed that each spring I is inclined and its attaching screw J is located to one side of the axis of the corresponding crank arm G so that even should the striking bar F, F', F² or F³ be swung upward until the crank arm G stands in vertical position, the spring I will 20 return the striking bar after being released by the player to sound the strings.

By raising the striking bars F, F', F² and F³ more or less and then releasing the same, the chords are sounded louder or softer. 25

Having thus described my invention, I claim as new and desire to secure by Letters Patent:

A stringed musical instrument of the class

Copies of this patent may be obtained for five cents each, by addressing the "Commissioner of Patents, Washington, D. C."

described, comprising a body, sets of melody and sets of accompaniment strings mounted 30 on the said body, the sets being spaced apart, bearing blocks mounted on the said body at opposite sides of the said accompaniment strings, striking bars extending across the said accompaniment strings and each 35 provided at the under side with a series of spaced cushions normally above the said accompaniment strings, crank arms on the ends of the said striking bars and journaled in the said bearing blocks, and springs attached to the said bearing blocks and connected with the said striking bars to move the latter into striking position after being first swung upward by the player and then released, the said springs being normally 40 in relaxed position and supporting the striking bars in inactive position and the cushions being out of engagement with the strings.

In testimony whereof I have signed my 45 name to this specification in the presence of two subscribing witnesses.

CHARLES HABERMANN.
